AUTOMOBILE HEATER

Filed July 31, 1939

UNITED STATES PATENT OFFICE

2,263,997

AUTOMOBILE HEATER

Henry J. De N. McCollum, Chicago, Ill.

Original application January 6, 1938, Serial No. 183,598. Divided and this application July 31, 1939, Serial No. 287,554

4 Claims. (Cl. 237—12.3)

My invention relates generally to automobile heaters, and more particularly to heaters of the internal combustion type. The present invention is an improvement on the heater shown in my prior applications, Serial No. 61,213, filed January 28, 1936, and Serial Nos. 120,523 and 120,524, filed January 14, 1937, and is a division of my copending application Serial No. 183,598, filed January 6, 1938.

In using an automobile heater of the internal combustion type upon an automobile, the gases of combustion from the heater are drawn into the intake manifold of the automobile engine. Compensation for this additional supply of gases to the intake manifold may easily be made by regulating the engine carburetor so as slightly to increase the idling speed of the engine. Of course this difficulty is encountered relatively infrequently, and only when the carburetor is very delicately adjusted to the needs of the engine.

In accordance with my invention, I provide means, controlled incidental to the operation of the heater control, for securing more uniform idling and normal operation of the engine irrespective of whether or not the heater is in operation. Such means may assume many different forms, but is disclosed herein as a means for automatically effecting an adjustment in the engine carburetor whenever the heater is placed in operation.

It is thus an object of my invention to provide an improved form of automobile heater having means for securing uniform operation of the engine irrespective of whether or not the heater is operating.

It is a further object of my invention to provide an improved means for automatically changing the idling adjustment of the engine carburetor whenever the heater is placed in operation.

Other objects will appear from the following description, reference being had to the accompanying drawing, which shows a heater in fragmentary vertical section mounted upon the dashboard of a vehicle, and illustrates the engine carburetor in elevation.

The heater comprises generally a combustion chamber 10 formed in a casting 12 which is secured to a back plate 14. The latter is connected by brackets 16 to the dash 18 of the vehicle. A radiator 20 is secured to the combustion chamber casting 12 and is surrounded by a shell 22 over which heat radiating fins 24 are secured. Within the radiator 20 is a circuitous passageway which terminates adjacent a nozzle 25 which forms means for compensating for changes in the

degree of vacuum in the intake manifold. This nozzle communicates with a passageway 26 in the casting 12 to which a fitting 28 is connected, the latter being connected by a conduit 30 with the intake manifold 32 of the engine. A valve 34 is engageable with the mouth of the nozzle 25 and is operable by means of a control button 36. Liquid fuel is supplied to the heater from a reservoir 38, which may be either the float bowl of the engine carburetor or a separate auxiliary reservoir for liquid fuel. The fuel is drawn from the reservoir 38 through a conduit 40 to a carbureting device 42 where the fuel is mixed with the proper amount of air to form a combustible mixture which is fed to the combustion chamber.

At the side of the combustion chamber 10 is located an igniter chamber which communicates with the combustion chamber through a large port 48. The igniter is preferably a coil of high resistance wire which may be electrically heated to incandescence and thereby ignite the mixture of liquid fuel and air passing through the combustion chamber. The combustion chamber is partially closed by a slightly porous refractory reigniter plug 52 which has passageways extending therethrough for the flow of the products of combustion.

The air from the passenger compartment of the vehicle is circulated past the heat radiating fins 24 by means of a fan 54 driven by a motor 56. A suitable switch mechanism 58 is mounted adjacent the end of the radiator 20 and is arranged to be controlled by the button 36 and by a strip of thermostatic bimetal 60 which is in heat conducting relationship with the radiator. This switch mechanism and its method of operation is more fully disclosed and claimed in my aforesaid application, Serial No. 120,524. It will suffice here to say that the switch is operable when the control button is pulled outwardly to open the valve 34, to close a circuit connecting the igniter with a source of current, and is operated thereafter by the thermostatic bimetal strip 60 to open the igniter circuit and to close a circuit connecting the fan motor 56 with the source of current. When the control button 36 is pushed inwardly, the valve 34 is closed and the circuits supplying both the fan motor and the igniter are opened.

As thus far described, the heater is disclosed in my aforesaid applications. The improvement of the present invention relates particularly to the provision of means for admitting additional air to the intake manifold of the engine whenever the heater is in operation.

To provide for automatic adjustment of the

engine carburetor, incidental to the operation of the heater, the valve stem 86 has an extension 102, the rearward end of which is guided in the fitting 28 threaded in the end of the combustion chamber casting 12. A Bowden wire 106 is secured to the end of the stem extension 102 and has its other end attached to a lever 108 mounted upon the engine carburetor 110. The lower arm 112 of the lever 108 normally rests against a fixed stop 114 on the carburetor 110 and itself forms a stop for the throttle valve lever 116, the adjustment screw 118 of the latter normally resting upon the upper surface 112 of the lever 108.

With this construction, it will be apparent that when the knob 36 is pulled outwardly (to the left), to initiate the operation of the heater, the Bowden wire will likewise be pulled to the left and thereby swing the lever 108 counterclockwise through a relatively small angle, thereby slightly opening the throttle valve. In this way, the idling speed of the automobile engine is automatically raised whenever the heater is in operation, while, when the heater is not in operation, the idling speed is that which is normally attained by proper adjustment of the throttle valve stop. While at normal idling speeds, the admixture of the gases of combustion from the heater to the charge fed to the engine cylinders may cause the engine to operate erratically, when the idling speed is increased, the gases of combustion from the heater will form a sufficiently smaller proportion of the mixture fed to the engine cylinders that the operation of the engine will not be noticeably impaired thereby.

It will thus be apparent that whenever the heater is in operation, the engine carburetor cannot be adjusted to a position in which the engine will not idle properly. It will be apparent to those skilled in the art that with different types of engine carburetors the adjustment to increase the proportion of fuel in the combustible mixture supplied by the carburetor to the engine, may be changed in different ways. It will be understood that, in its broader aspects, my invention resides in making a suitable adjustment in the engine carburetor controlling means to compensate for the gases of combustion fed to the intake manifold of the engine during the period that the heater is in operation.

While I have shown and described a preferred embodiment of my invention, it will be readily understood by those skilled in the art that variations may be made in the construction disclosed without departing from the basic features of my invention. I therefore do not wish to be limited to the precise construction disclosed, but

wish to include within the scope of my invention all such modifications and variations which will readily suggest themselves to those skilled in the art.

5. What I claim as new and desire to secure by United States Letters Patent is:

1. In an automobile having an internal combustion engine provided with a carburetor, a heater having a control element, a throttle valve, a stop for limiting movement of said throttle valve toward closed position, and means operated by said control element to shift said stop and prevent movement of said throttle valve to its closed position.

15. 2. In a heating system for an automobile having an internal combustion engine provided with a throttle valve controlled carbureting system and employing a heater of the internal combustion type exhausting its products of combustion into the intake manifold of the engine, the combination of a manually operable element to control the operation of the heater, a stop to limit the degree of closing movement of the throttle valve of the engine carbureting system, and means actuated by said manually operable control element effectively to change the position of said stop in a manner to prevent closure of said throttle valve to its normal idling position.

20. 3. In a heating system for an automobile having an internal combustion engine provided with a carburetor having an idle adjusting throttle valve stop, an internal combustion type heater having means for conveying the products of combustion therefrom to the intake manifold of the automobile engine, a manually actuated element for controlling the operation of said heater, and means operated by said manually actuated element, when the latter is moved to a position to render said heater operative, to change the idle adjusting stop in a manner to prevent movement of the throttle valve to its normal idling position.

25. 4. In a heating system for an automobile having an internal combustion engine provided with a throttle valve, a carburetor, and employing a heater of the internal combustion type exhausting its products of combustion into the intake manifold of the engine; the combination of a manually operable element to control the operation of the heater, a lever to limit the degree of closing movement of the throttle valve of the engine carbureting system, and a Bowden wire connection between said manually operable control element and said lever effective to change the position of said lever in a manner to prevent movement of said throttle valve completely to its normal idling position.

HENRY J. DE N. McCOLLUM.
